(57) **CLAIM**

The ornamental design for a shaving device handle with hole, as shown and described.

DESCRIPTION

FIG. 1 is a top perspective view of a shaving device handle with hole;

FIG. 2 is a top view thereof;

FIG. 3 is a bottom partial view thereof;

FIG. 4 is a left side view thereof, the right side view being a mirror image of the left side view; and,

FIG. 5 is a front view thereof.

The broken lines in the figures are for the purpose of illustrating portions of the shaving device handle with hole, which form no part of the claimed design.
